UNITED STATES PATENT OFFICE

BENJAMIN F. FITCH, OF GREENWICH, CONNECTICUT, ASSIGNOR TO MOTOR TERMINALS COMPANY, OF WILMINGTON, DELAWARE, A CORPORATION OF DELAWARE

APPARATUS FOR TRANSFERRING FREIGHT

Application filed October 27, 1928. Serial No. 315,448.

This invention relates to a freight handling system wherein removable containers are provided which are adapted to be transported by a vehicle to a transfer point and there removed with the contained load from the vehicle, and thereafter another loaded container deposited on the vehicle. As such containers to be efficient must be of considerable size, some sort of hoisting and transporting mechanism is essential in removing or replacing the loaded container. It is an object of this invention to provide such hoisting and transporting mechanism in a very simple and efficient form, suitable for installation at comparatively small expense.

My invention is more particularly concerned with the transfer of containers to and from freight cars of electric interurban lines having overhead trolley wires. The invention contemplates a superstructure located adjacent the side of the railway track and having an overhead trackway on which is a traveling crane which may raise and transport laterally a removable body, associated with means for shifting the trolley wire out of the way of the crane cables suspending the container, so that the crane may transport the body laterally.

More particularly, I propose in this invention to carry that portion of the trolley wire which is at the transfer point by a laterally shiftable carriage mounted on the superstructure. This carriage is normally in position directly above the track and carries the trolley wire or its equivalent beneath the crane support. When it is desired to use the crane, the carriage supporting the trolley wire section is simply shoved laterally to one side or the other, thus clearing the space for the lateral movement of the cables depending from the crane. Such an apparatus is illustrated in the drawings hereof, and is hereinafter more fully explained. The essential novel features of the invention are summarized in the claims.

In the drawings, Fig. 1 is an elevation transversely of an electric railway track and two side superstructures, and an overhead crane trackway; Fig. 2 is a sectional elevation thereof at right angles to Fig. 1, being on a

plane indicated by the line 2—2 on Fig. 1; Fig. 3 is a plan of such installation, the roof being omitted; Fig. 4 is a diagrammatic elevation illustrating the relation of the removable container, the trolley wire carriage and the traveling crane; Fig. 5 is a detail in vertical section adjacent one end of the continuous trolley wire.

As shown in Figs. 1, 2, 3, A represents an electric railway track, B the usual suspended trolley wire therefor, and C an electric flat car adapted to travel on such rails by electric power. This flat car may have a cab c and a trolley pole c'. D indicates the removable body, which may be mounted on the flat car in the rear of the cab. This body is preferably of such size that it may also readily fit on an automobile truck (as indicated at E in Fig. 1) so that the body may be interchanged as desired between the truck and flat car. The body may be provided with suitable doors d, and at the eves with hooks or eyes d' or other means for attachment of raising cables.

In Figs. 1, 2 and 3, I have shown superstructures located opposite each other on both sides of the track and connected by a bridge, thus providing a continuous overhead support for the crane and trolley wire carriage. Such superstructure has upright posts 10, suitable cross beams 11 and tie members 12. It carries a pair of crane tracks 15 bridging across the railway track space. These tracks are shown as mounted on brackets 16 carried by the posts 10.

The tracks 15 carry a suitable crane 20 having four raising cables 21 terminating at their lower ends in hooks or eyes. Mounted on the crane frame is a suitable mechanism for pulling up these cables as a unit. The mechanism shown comprises a rotatable screw 24 (Fig. 3), a travel nut 25 thereon, and guide bars 26 for the nut. The cables 21 pass upwardly over sheaves 27 and thence around sheaves 28 and 29, and are finally anchored to the nut 25. Accordingly, the rotation of the screw 24 operates to simultaneously raise or lower all four of the lift hooks. The screw may be rotated by any suitable means, as for instance an electric motor 30, which may receive its power from the trolley circuit. The crane

preferably has also a motor 31 geared with one of the supporting wheels 32, whereby the crane may be shifted along its track.

Normally the raising cables and lift hooks 5 are located a considerable distance above the line of the trolley wire B and entirely out of the way of the electric car and the trolley pole. Accordingly, the car may run freely 10 past the transfer structure. It is desirable 10 however, that the trolley wire be normally continued through the structure either in the form of the wire or an inverted trough, so that the car may run continuously without 15 attention to the trolley pole, when the hoist mechanism is not in use.

However, to use the hoist mechanism to raise a body and shift it laterally to or from the car, it is necessary to provide some means whereby the trolley wire will not interfere 20 with the supporting cables. To accomplish this, I terminate the trolley wire proper adjacent the two ends of the superstructure, and support the free ends by suitable guides b (Fig. 5), and I mount the intermediate section 25 of the trolley wire on a traveling carriage which may be located directly over the railroad track or may be shifted laterally to carry the wire to idle position, leaving an open gap for operation of the raising cables. Such construction will now be described.

On the supporting posts 10, I secure suitable brackets 40 which carry tracks 41 bridging the railroad trackway, and on these tracks I mount a light carriage 42 which supports 35 an intermediate section 43 of the trolley wire by brackets 44 or otherwise. This section is shown as an inverted trough adapted to be engaged by the flanges of the trolley wheel, but if desired, it could be a wire or bar engaging 40 in the groove of the trolley wheel. The section 43 is adapted to align with the permanent trolley wires B, as shown in Figs. 2 and 5, and thus make a continuous guiding member for the trolley wheel as the car runs 45 past the transfer structure. The carriage is normally locked in this central position, as for instance by a suitable latch bolt 45 (Fig. 1) thereon, coacting with the trackway. When it is desired to use the crane, it is only necessary 50 to manually unlock the carriage 42 from its central position and shove it to one side or the other as illustrated in broken lines in Fig. 1.

The intermediate trolley wire section 43 55 may be connected electrically with the trolley wire by a suitable conductor so that substantially continuous current is provided to the car motor, or the section may be "dead" and momentum relied on to carry the trolley car through the hoist structure.

In ordinary operation of the construction described, the trolley carriage 42 stands in the mid position as shown in Fig. 1 and the electric car operates in a normal manner without regard to the transfer apparatus. The

crane at this time stands in any lateral position with the cables elevated out of the way. Now, when it is desired to use the transfer mechanism, the trolley car with its body is brought into position beneath the crane trackway as shown in Fig. 2, the trolley carriage is unlocked and shifted out of the way toward the opposite side from that to which the load is to be transferred. The crane is brought over the body and the cables lowered 70 and connected to the body, as indicated in broken lines in Fig. 1. The body may then be raised by the electric motor 30 and transported laterally by the motor 31, both receiving current from the trolley circuit. The body 75 is thus brought to the side of the railroad track, where it may for instance be deposited on suitable supports or "horses" as indicated at F in Fig. 1, or, if desired, the body may be deposited on the automobile truck E 80 also indicated in that figure. The reverse operation from that described will transfer a body from the support or truck onto the electric flat car, whereby it may be transported. 85

I claim:

1. In a freight transferring apparatus, the combination of a crane trackway spanning an open space, a crane adapted to move on said trackway and having a depending cable, a carriage trackway spanning such space, a carriage movable on its trackway, trolley wires leading from opposite directions to points adjacent the transferring apparatus, and a trolley guide adapted to align with the two sections of the trolley wire and supported by said carriage, said cable being adapted to pass through the normal position of the trolley wheel guide.

2. In an apparatus for transferring freight, the combination with a railway track, of a supporting structure alongside of the track, a trackway on said structure, a traveling crane on such trackway and having a depending cable, a trolley carriage mounted on the structure and movable independently of the traveling crane, and a trolley wheel guide carried by said carriage, said cable being adapted to pass through the normal position of the trolley wheel guide.

3. In an apparatus for transferring freight, the combination with a railway track, of a supporting structure alongside of the track, two trackways on said structure, one higher than the other, a traveling crane on the upper trackway and having a depending cable, a carriage on the lower trackway, and a trolley wheel guide on the carriage adapted to register with trolley wires at either end of the structure, said cable being adapted to pass through the normal position of the trolley wheel guide.

4. In an apparatus for transferring freight, the combination with a railway track having a trolley wire above it, of supporting structures on opposite sides of the

- track connected by a bridge above the track, two trackways on said structures and bridge, one higher than the other, a traveling crane on the upper trackway and having a depending cable, a carriage on the lower trackway, and a trolley wheel guide on the carriage, said cable being adapted to pass through the normal position of the trolley wheel guide. 5
5. The combination of a railway track, of supporting structures on opposite sides thereof, a trackway carried by said structures and bridging across the space above the railway track, a traveling crane on such trackway equipped with raising mechanism adapted to engage a removable body on a car on the track, laterally traveling means for supporting a trolley wheel guide in registration with trolley wires below the crane trackway, said means being movable independently of the crane to either side to clear the way for the trolleying operation of the traveling crane. 10
6. An apparatus for transferring freight, comprising the combination with an electric railway having a track and an overhead trolley wire, an overhead crane adapted to raise a body from a car on the track, and an overhead carriage independent of the crane carrying a trolley-wheel-guide, such carriage being shiftable laterally to leave an unobstructed space for the shifting of the supporting cables depending from the crane. 15
7. The combination with a railway track, a trolley wire above it, of a structure along- 35 side of the track having a crane trackway extending above the railway track, a crane movable along said trackway, a raising cable depending from said crane and adapted to be connected to a removable body on an electric car below the crane, and means mounted on an independent track and movable independently of the crane for shifting a section of the trolley wheel guide out of the way to enable the hoist cable to be shifted laterally. 40
- 45 8. In an apparatus for transferring removable bodies to or from electric cars, the combination of a railway track on which the cars may run, a trolley wire above said track, a pair of structures opposite each other and on opposite sides of the track, and connected together above the plane of the trolley wire, a transverse trackway on said structures bridging the space above the railway track, a traveling crane on such bridging track having hoisting mechanism and four depending cables adapted to be lowered to engage a removable body on the railway car, there being space within the structure on either side of the railway track for receiving or depositing a removable body, a second transverse track bridging the space above the railway track, a carriage on said second track, a trolley guide carried by the carriage and adapted to register with the trolley wire to make a continuous path for the trolley wheel from one end of the structure to the other, said carriage being shiftable laterally to either side of the railway track independently of the traveling crane. 50
9. In an apparatus for transferring freight to or from electric cars, the combination of a railway track and a trolley wire above it, a structure along side of the track, hoist mechanism mounted on said structure and adapted to be moved over the track and engage a movable body on a car on the track, the two sections of the trolley wire at opposite ends of the structure being interrupted, a trolley wheel guide between such interrupted ends adapted to register therewith, and a bodily movable carriage supporting said trolley wheel guide for permitting movement of said guide laterally independently of the hoist mechanism. 55
10. The combination with a railway track and a trolley wire above it, of supporting structures at opposite sides thereof carrying a bridge over the railway track, hoisting mechanism carried by such combined structure and adapted to be moved from either side to a position above the track, and a bodily movable wheeled carriage laterally shiftable below the hoist mechanism and relative to it for carrying a trolley wheel guide adapted to align with the trolley wire or be out of alignment therewith. 60
- In testimony whereof, I hereunto affix my signature.
- BENJAMIN F. FITCH.
